SIMILAR ARTICLE

Helen M. Mullen, Seattle, Wash.

Application February 16, 1953, Serial No. 23,629

Term of patent 7 years

(Cl. D58—6)

To all whom it may concern:

Be it known that Helen M. Mullen, a citizen of the United States, residing at 6033 Kelden Place, Seattle 5, Washington, has invented a new, original, and ornamental Design for a Combined Bottle and Applicator or Similar Article, of which the following is a specification, reference being had to the accompanying drawing, forming a part thereof, in which:

Figure 1 is a front elevational view of a combined bottle and applicator or similar article, showing my new design.

Figure 2 is a side elevational view thereof.

Figure 3 is a top plan view thereof, partially in section, taken on the line 3—3 of Figure 1.

The rear view of the combined bottle and applicator is plain.

I claim:

The ornamental design for a combined bottle and applicator or similar article, as shown and described.

HELEN M. MULLEN.
